UNITED STATES PATENT OFFICE.

OSCAR L. OWEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

TOP-ROLL SADDLE.

1,258,701.

Specification of Letters Patent. Patented Mar. 12, 1918.

Application filed March 16, 1917. Serial No. 155,164.

To all whom it may concern:

Be it known that I, OSCAR L. OWEN, a citizen of the United States, residing at Whitinsville, county of Worcester, and Commonwealth of Massachusetts, have invented an Improvement in Top-Roll Saddles, of which the following description, in connection with the accompanying drawings, is a specification.

10 My invention relates to improvements in spinning frames; and it consists in the peculiar and novel construction of the connection between the weight stirrup and front top-roll saddle, more fully set forth hereinafter.

15 The object of this invention is to provide means for positively preventing any accidental separation of the weight stirrup from its supporting saddle member whenever the top-roll saddle is removed from the

20 frame.

In the drawings forming part hereof Figure 1 shows a transverse sectional view of a part of a spinning frame showing my improved mechanism in operative position.

25 Fig. 2 is an enlarged sectional elevation of the front saddle showing the means for connecting the weight-stirrup to the saddle. Fig. 3 is a transverse sectional view through the saddle and weight stirrup retaining screw. Fig. 4 shows the construction of the upper part of the weight-stirrup.

30 In the drawings 1 indicates the part of a spinning frame supporting the roll stands 2 with the usual bottom rolls 3 and top-rolls 4. 5 represents the front saddle, 6 the back saddle, and 7 my improved weight-stirrup. The upper end of the weight-stirrup is provided with a rectangular opening 8 of such dimensions as to slide easily over the roll bearing end of the front saddle. The upper edge of this opening is slidably mounted on the top of the front saddle and transmits the pressure of the weighting mechanism through the saddle to the top rolls. In the 45 upper outside edge of the weight-stirrup a U shaped notch 9 is formed which embraces the annular groove 10 of the retaining screw 11 threaded into the boss 12 on top of the front saddle.

50 Although the above is my preferred construction I do not desire to be restricted to the use of a stirrup with a notch in the

upper edge thereof as a modified form may be made using a stirrup with a comparatively narrow upper part but without a 55 notch therein.

By my construction the top of the weight-stirrup is confined in the inclosure formed by the grooved head of the retaining screw and the top of the saddle thus preventing 60 the separation of the stirrup from the saddle without first removing the retaining screw from its connection with the saddle.

Having thus described the invention what is claimed is:—

65 1. A retaining device for stirrups of top-roll saddles comprising a saddle with a stirrup bearing surface; a stirrup slidably mounted thereon; a rotating member in adjustable relation with the saddle and located 70 above the upper outside edge of the stirrup; an annular groove in the rotating member, said groove coöperating with the upper outside edge of the stirrup to positively lock the stirrup and saddle together.

75 2. In a top-roll saddle the combination of a saddle provided with a stirrup bearing surface; a stirrup having an opening for the saddle, the upper edge of said opening being slidably mounted on the saddle; a notch located in the upper outside edge of the stirrup; a rotating member adjustably connected with the saddle and located above the upper outside edge of the stirrup; an annular groove in the rotating member, said 80 notch coöperating with said groove to retain the stirrup in positive locking relation with the saddle.

85 3. In a top-roll saddle the combination of a saddle provided with a stirrup bearing 90 surface; a stirrup having an opening for the saddle, the upper edge of said opening being slidably mounted on the bearing surface of the saddle; a rotating member in adjustable relation with the saddle and located 95 above the stirrup bearing surface; an annular groove in the head of the rotating member; an inclosure formed by said groove and said bearing surface, wherein the top part of the stirrup is confined and positively locked 100 to the saddle.

In testimony whereof, I have signed this specification.

OSCAR L. OWEN.
